MULTIPLE FUSE

William C. Linton, Washington, D. C., assignor
to Fuse Indicator Corporation, Washington,
D. C., a corporation of Delaware

Application March 6, 1939, Serial No. 260,160

4 Claims. (Cl. 200—121)

The present invention relates to multiple fuses of the plug type having means for visibly indicating the ruptured or blown condition of the thermal elements thereof, all of which are confined in a single unitary structure. The conventional type of multiple plug fuses have arranged therein a plurality of fuse links and a rotatable member which selectively and in succession causes the fuse links to be connected in series with the contact terminals of the fuse plug as they become blown or ruptured by short circuiting or overloading the electrical circuit in which the fuse plug is connected. To the contact terminals of this type of multiple fuse plugs is connected a shunt circuit having a glow lamp and leak resistor included therein, which latter are arranged in series with the contact terminals of the fuse plug but in parallel to the fuse links, which latter are also connected in series to the contact terminals of the fuse plug, whereby, when a fuse link blows or becomes ruptured, the glow lamp will be caused to give off or emit a visible signal, indicating the inoperative condition of such fuse link. By turning the rotatable member, a new fuse link will be connected to the contact terminals of the fuse plug, thereby again completing the electrical circuit and as no current will pass to the glow lamp, the latter will again be extinguished. Movable contacts must necessarily be carried by the rotatable member, whereby the fuse links and shunt circuit having the glow lamp arranged therein may be selectively connected to the contact terminals of the fuse plug and it is an object of the present invention to provide a new and novel manner of mounting a glow lamp, resistor and connections therefor upon such rotatable members, whereby, the several parts thereof may be easily and readily assembled for materially decreasing the cost associated with the manufacture of such multiple indicating fuse plugs and, at the same time, effect a positive connection between the movable contacts and the contact terminals of the fuse as well as safeguarding the fuse links and the movable contacts from becoming damaged or rendered inoperative by eliminating all possible chances of the molten metal coming in contact therewith which is given off by the blowing or melting of a fuse link when a short circuit occurs. Other objects of the invention will be in part obvious and in part pointed out hereinafter.

In order that the invention and its mode of operation may be readily understood by persons skilled in the art, I have in the accompanying drawings and in the detailed following descrip-

tion based thereupon, set out an embodiment of the same.

In the drawings:

Fig. 1 is a top plan view of a multiple fuse embodying the present invention. 5

Fig. 2 is a top plan view of the casing of the fuse plug with the signal lamp and its cover removed.

Fig. 3 is a vertical transverse sectional view through the completed fuse plug. 10

Fig. 4 is a vertical transverse sectional view of the fuse plug taken at right angles to Fig. 3.

Fig. 5 is a horizontal section taken on the line 5—5 of Fig. 3 in the direction of the arrow points.

Fig. 6 is a horizontal section taken on the line 15 6—6 of Fig. 4 in the direction of the arrow points.

Fig. 7 is a side elevation of the connector block.

Fig. 8 is a detail vertical section through the rotatable member or core.

Fig. 9 is a plan view of the disc separator or 20 partition.

Fig. 10 is a detail perspective view of one of the fuse links.

Fig. 11 is a vertical section through a fuse plug showing a slightly modified form of the invention. 25

Fig. 12 is a horizontal section taken on the line 12—12 of Fig. 11 in the direction of the arrow points.

Fig. 13 is an enlarged detail section, and 30

Fig. 14 is a plan view of a fiber washer constituting an element of the fuse plug.

Referring now more particularly to Figs. 1 to 10 inclusive of the drawings wherein I have illustrated a conventional type of multiple fuse plug having a glow lamp indicator attached thereto, which comprises a tubular casing 1 molded from suitable insulating material and having a central tapered bore extending entirely therethrough.

Fitted within this bore of the casing 1 is a rotatable member or core 2 and which core is retained within the casing 1 by means of a cap or base 3. A standard threaded contact shell 4 connects the base 3 to the casing 1 and has a polygonal opening formed therein which receives a correspondingly shaped boss 5 formed with the base 3, which prevents the latter from rotating with respect to the casing 1. The inner face of the base 3 is provided with an upstanding conical-shaped boss 6 and the casing 1, core 2 and base 3 are preferably molded from suitable insulating materials.

The upper end of the core 2 is provided with a pocket 7 preferably of a square configuration in which is seated a lug 8 formed with the lower face of a block 9 in order that when 40

the pocket 7 is seated in the lug 8, the block 9 is held in a fixed position relative to the core 2 and the base 3.

Referring now to Fig. 11, the base 3 is provided with a central bore 10 which is in communication with the central bore of the casing 1.

Extending through the base 3 and into the central bore of the casing 1 is a fiber washer 11 which is held in place by a screw 12.

Extending through the fiber washer 11 and into the central bore of the casing 1 is a wire 13 which is connected to the base 3.

Extending through the fiber washer 11 and into the central bore of the casing 1 is a wire 13 which is connected to the base 3.

this block is rotated, the core 2 will be carried therewith. This block 9 may form an integral part of the core 2 but is herein shown as being a separable element in order that the parts may be more easily and readily assembled.

A central contact 10 in the form of a metallic headed rivet extends through the base 3, the bore 6 thereof, the core 2 and the block 9. Formed within the upper face of the block 9 is a square recess 11 in which is seated a correspondingly shaped plate 12 and a drop of solder 13 extends over the upper end of the rivet 10 and this plate 12 for permanently connecting the block 9 and core 2, whereby the rivet will rotate with the core during its turning movement. The headed end of the rivet 10 provides the usual contact for engagement with the central contact of a cutout base included in an electrical circuit.

Arranged about the lower end of the casing 1 20 is a plurality of substantially U-shaped fuse links 14, each having one arm 15 wedged between the contact shell 4 and the outer face of the casing 1 and a parallelly extending arm 16, each of which is seated within recesses formed within 25 the inner face of the casing 1 and arranged between this casing 1 and the rotatable core 2. The core 2 is provided with a centrally located chamber and a vertical opening 17 which extends through one wall of the core and communicates with this chamber of the core. Seated upon the boss 6 of the base 3 is a disc 18 cut from a sheet of fiber, Bakelite or other similar insulating materials which has an opening 19 formed therein for receiving the shank portion of the rivet 10 and a lipped projection 20 which extends through the vertical slot 17 of the core 2, thereby dividing the chamber within the core 2 into an upper compartment 21 and a lower compartment or explosive chamber 22. Arranged within 30 the upper compartment 21 is a spring contact member 23 which has one end secured to the shank portion of the rivet 10 and its opposite end projecting through the slot 17 of the rotatable core so that it may have frictional contact with the upper end 24 of the arm 16 of the fuse links and this spring contact member 23 being affixed to the rivet 10 will rotate therewith as well as with the core 2.

Each arm 16 of a fuse link is provided with 50 a reduced portion 25 and a lower leg portion 26, both of which at times register with the explosive chamber 22 formed within the core 2. When a short circuit occurs, the fuse link which is connected to the contact terminals of the fuse will become overheated and the reduced portion 25 will be the first to melt and drop from the fuse link, thereby blowing or rupturing the same. The molten metal given off by such blowing of the fuse link will drop within the explosive chamber 22 and be confined therein by means of the partition 18 and this latter partition will also prevent the molten metal from coming into engagement with the spring contact 23 which is likely to damage the same or render the contact 65 inoperative. The gases under pressure given off by the blowing of the fuse link will escape from the explosive chamber 22 between the lower end of the casing 1 and the base 3 to the atmosphere in the usual manner.

70 The indicating means for giving off a visible signal as to the blown condition of the fuse link consists of a miniature neon glow lamp 27 having one lead wire 28 thereof connected to the rivet 10 by means of the soldered connection 75 13 and the other lead wire 29 of the lamp has one

extremity connected to a leak resistor 30. Formed within the core 2 is a pocket or vertically extending opening 31 in which the leak resistor 30 is arranged. This leak resistor preferably consists of a plastic composition which is forced 5 within the pocket 31 for filling the same and while in a plastic state, one extremity of the lead wire 29 is embedded therein. When this plastic composition is allowed to dry, the lead wire 29 will be permanently attached thereto, thereby eliminating any solder or other connecting elements or composition between the lead wire 29 and the resistor.

Formed within the lower end of the core 2 and communicating with the pocket 31 is an enlarged 15 pocket 32 in which is arranged a ball contact member 33 and a coil spring 34 which normally tends to force the ball outwardly from the pocket 32. One end of the coil spring 34 is embedded and connected with the lower end of the resistor 29 30 and the ball 33 being normally urged outwardly, comes in contact with the lower ends 26 of the fuse links. When a fuse link becomes blown or ruptured, the lower end 26 of the arm 16 thereof will remain intact and connected to 25 the arm 15 thereof, which latter is also connected to the shell 4 and in this manner, at all times establishes a connection between the glow lamp and the contact terminal 4 should any one or all of the fuse links become blown or ruptured. 30

The glow lamp 27 is housed within a casing 35, which latter has a "snap-on" connection as at 29 with the block 9 and acts as a handhold whereby the operator may turn the block together with the core 2 attached thereto in the 35 direction of the arrow, as is conveniently illustrated in Fig. 1 of the drawings. This cover 35 is preferably molded from a transparent material in order that the rays of light emitting from the lamp 27 may project therethrough and also, this cover 35 may be molded in various transparent colors, which colors may be used as marks for designating the particular voltage or amperage rating of the fuse plug to which it is applied, such as 15 a.—125 v. molded with the 40 top of the cover 35 and illustrated in Fig. 1 of the drawings.

In Figs. 11 to 14 of the drawings, I have illustrated another conventional multiple plug type fuse having my invention applied thereto and which consists of a cup-shaped casing 36 having a standard threaded contact shell 37 attached thereto and a rotatable core 38 arranged within the casing 36. This core 38 has a plurality of longitudinally extending grooves 39 formed with 55 in its outer wall and in each of these grooves is arranged a fuse link 40. The lower ends of these fuse links are joined together by means of a hub portion 41, all of which are cut from a single sheet of fusible material. A spring contact member 42 extends through an opening formed within the casing 36 having one end thereof connected to the shell 37 and its opposite end 43 being capable of selectively engaging the fuse links 40. A metallic ring 44 corresponding 60 in shape to the fiber washer 45, as is better illustrated in Fig. 14, fits about the core 38 and is in contact with the upper ends of the fuse links 40. This ring 44 is retained in place upon the core by means of the fiber washer 45.

The outer or upper face of the core 38 lies flush with the upper face of the casing 36 and this casing has an annular recess or ledge 46 formed therein in which is seated the ring 44 and the washer 45. The block 47 which is connected to 70

the upper end of the core 38 is in the form of a circular disc which covers the upper ends of the core and the casing 36.

A central contact member 48 is in the form of a metallic rivet and extends through the casing, core and block 47 and by means of the soldered connection 49, retains the core within the casing 36 as well as the block thereupon.

Seated upon a boss formed within the casing 10 36 is a contact member 50 and this latter has rotatable engagement with the shank portion of the rivet 48. This contact member 50 being semi-spherical, provides a lower bearing for the core 38 as well as a more positive connection between 15 the hub portion 41 of the fuse links and the central contact or rivet 48.

The glow lamp 51 is seated upon the block 47 and has one lead wire 52 connected to the rivet 48 by means of the solder 49, whereas the 20 other lead wire 53 has its outer extremity embedded within a plastic leak resistor 54. This resistor 54 is seated within a pocket or recess formed within the block 47 and is also electrically connected to the ring 44 by means of a pin or 25 other conductor 55.

Formed with the block 47 and extending from the upper face thereof are the flanges or ribs 56, which latter have a "snap-on" connection with the cover 57 and this cover not only houses the 30 lamp 51 but provides a handhold for turning the core 38, whereby the fuse links may be selectively brought into engagement with the terminals 43 of the spring contact.

During the normal operation of this fuse plug, 25 the current will flow from the shell 37 through the spring contact 42, through a fuse link 40 to the central contact 48 but should this latter fuse link become blown or ruptured, the current will flow from the spring contact 42 through that 40 remaining portion or the upper end of the blown fuse link to the ring 44, through the leak resistor 54 to the lamp 51 and then return through the central contact 48, thereby causing the lamp to glow for giving off a visible signal as to the 45 blown or ruptured condition of the fuse link. By turning the core 38, a new or good fuse link 40 will be brought into engagement with the spring contact 48 for again causing the current to flow therethrough and as no current will pass to the 50 lamp 51, the latter will again be extinguished.

From the foregoing, it will be apparent that I have established a new and novel manner of mounting a lamp indicator upon the rotatable member of a conventional multiple plug type 55 fuse as well as mounting movable contacts and other elements of the electrical circuit in which the lamp is included upon such rotatable member, whereby the several parts thereof may be more readily and easily assembled, thereby materially 60 reducing the cost associated with the manufacture of such indicating fuses of the multiple plug type.

Manifestly, the construction herein shown is capable of considerable modification and such 65 modifications as come within the scope of my claims, I consider within the spirit of my invention.

I claim:

1. A multiple fuse plug comprising a body 70 formed with a chamber open at its upper end and having its annular wall formed with a side opening, an internal annular ledge being formed adjacent the open end of the body, a boss projecting inwardly from the lower end of said body 75 into said chamber, a stationary contact in said

chamber having a shank extending longitudinally of the body and passing outwardly through the side opening thereof, a shell terminal fitting about said body and engaging the outer portion of the shank of said contact, a rotatable core 5 in said body, a bearing of conductive material between the inner end of said core and the end of said boss, a fuse having a hub disposed between the core and said bearing and arms extending 10 from the hub longitudinally of the core in spaced relation to each other circumferentially of the core for successive engagement by the stationary contact when the core is turned to adjusted positions, a flange about the outer end of said core, 15 a ring of conductive material fitting about said core against said flange and engaged by outer ends of the fuse arms, a washer of insulating material fitting upon said ledge and engaged by said ring with a portion for spacing said ring from said stationary contact, a cap for the upper end of said body having a boss extending therefrom and seated in a recess formed in the outer end of the core for turning engagement therewith, 20 a center terminal rivet passing through the core 25 and bearing with its end portions extending through the cap and the lower end of the body and headed to hold the bearing and the core and the cap in place, said cap being formed with a socket and the flange of the core with an opening between the socket and the conductive ring, 30 a plastic leak resistor composition in said pocket, means extending through the opening of the flange for connecting said conductive ring with said composition, a signal lamp having a conductor connected to one end of said rivet and a second conductor connected with the composition, and a casing of light penetratable material carried by said cap in enclosing relation to the signal lamp and serving as means for imparting 35 turning adjustment to the cap and the core. 40

2. A multiple indicating fuse comprising a casing, a rotatable core arranged within said casing and having a chamber formed therein, a central contact connected to said rotatable core, a threaded shell contact connected to said casing, a spring contact member connected to said central contact, a plurality of fuse links arranged within said casing whereby said spring contact may selectively engage said fuse links, a glow lamp indicator carried by said rotatable core having one lead wire thereof connected to said central contact, said rotatable core having a pocket formed therein, a spring actuated ball contact arranged within the pocket of said core and adapted to selectively engage said fuse links and a leak resistor connecting said ball contact with the other lead wire of said lamp. 55

3. A multiple plug fuse comprising an outer casing, a rotatable core arranged within said casing and having an explosive chamber formed therein, a boss formed with said outer casing and extending vertically within the explosive chamber of said core, a central contact extending through said boss and connected to said rotatable core, a threaded contact shell carried by said casing, a plurality of fuse links, a partition seated upon said boss for dividing said explosive chamber into separate sections, a spring contact member arranged within one of the sections of said explosive chamber and connected to said central contact whereby with the rotation of said core, said spring contact may selectively engage one end of each of said fuse links and means for electrically connecting the opposite ends of said fuse links to said threaded contact shell. 75

4. A multiple indicating plug fuse comprising a casing, a core rotatably mounted within said casing, a central contact, a threaded contact shell, a plurality of fuse links adapted through the rotation of said core to be selectively connected in series with said central contact and said threaded contact shell, one end of said core terminating flush with the outer face of said casing and having a pocket formed therein, a block seated upon the outer face of said casing, a lug extending from said block and seated within the pocket of said core whereby said block will re-

tate with said core, said core and block having aligning recesses formed therein, a leak resistance arranged within the recesses of said block and core, means for electrically connecting one end of said leak resistance with said threaded contact shell, a cover detachably connected to said block, a glow lamp indicator arranged within said cover and means for connecting said glow lamp with said central contact and said leak resistance.

10

WILLIAM C. LINTON.
